UNITED STATES PATENT OFFICE.

WILLARD F. RICHARDS, OF BUFFALO, AND WILLIAM A. TURBAYNE, OF LANCASTER, NEW YORK, ASSIGNORS TO GOULD COUPLER COMPANY, OF NEW YORK, N. Y.

DYNAMO-ELECTRIC MACHINE.

No. 830,849.

Specification of Letters Patent.

Patented Sept. 11, 1906.

Application filed August 12, 1905. Serial No. 273,955.

To all whom it may concern:

Be it known that we, WILLARD F. RICHARDS, residing at Buffalo, and WILLIAM A. TURBAYNE, residing at Lancaster, in the county of Erie, State of New York, citizens of the United States, have invented a new and useful Improvement in Dynamo-Electric Machines, of which the following is a specification.

This invention relates to dynamo-electric machines, and more particularly to the mechanical construction and arrangement of the parts of a generating set employed in railway-car lighting and composed of two dynamos located side by side, with their armatures mounted on a common shaft and in which one of the machines is a main generator and the other an auxiliary dynamo utilized in the regulation of the main generator.

One object of the invention is to secure the several rotating parts of the machines on the shaft, by means which simplify the manufacture and reduce the construction of the apparatus and enable the parts thereof to be assembled and dismantled with the minimum labor and loss of time; to completely inclose and protect the apparatus from the weather and from dust and dirt and at the same time render the various parts of the machine readily accessible for inspection, cleaning, repairs, &c.; to provide simple and efficient guard means for preventing the lubricating oil for bearings from working its way onto the armatures and commutators of the machines, and to improve the construction of the apparatus in the respects hereinafter specified and set forth in the claims.

In the accompanying drawings, consisting of three sheets, Figure 1 is a longitudinal sectional elevation of a dynamo-electric apparatus embodying the invention. Fig. 2 is a fragmentary side elevation of the auxiliary dynamo. Fig. 3 is an end elevation, on an enlarged scale, of the machine looking from the left in Fig. 1. Fig. 4 is a transverse sectional elevation, on an enlarged scale thereof, in line 4-4, Fig. 1, looking toward the left. Fig. 5 is a sectional elevation, on an enlarged scale, in line 5-5, Fig. 1. Figs. 6 and 7 are fragmentary sections, on an enlarged scale, of the shaft-bearings and oil-guards at the opposite ends of the main dynamo.

Like letters of reference refer to like parts in the several figures.

A represents the field-magnet frame or ring of the main generator or dynamo, and A' and B the armature and commutator, which are secured on the armature-shaft C. The field-magnet frame, which preferably consists of an open-ended cylindrical shell, is secured in any desired manner to a suitable support, usually the car-truck, (not shown,) and constitutes the supporting-frame for the several parts of the apparatus. The opposite ends of the hollow frame A are closed by ends or heads D D', which are detachably secured to the frame by bolts d or other means. The heads are preferably hollow, thus forming lubricating-chambers for the armature-shaft, and the opposite walls thereof are provided with central holes, in which are secured bearing-bushings d' d'' by set-screws d''' or other means. The hollow head D, which is the left-hand head in the drawings, has an extended annular portion E, which surrounds the commutator of the main dynamo and is provided with openings e, Figs. 1 and 4, opposite to the dynamo-brushes e', through which openings access can be had to the brushes for adjusting and renewing them or for any other reasons. The commutator, brushes, and brush-holders may be of any usual or suitable form; but the brush-holders e' are preferably secured to a supporting-ring e'', Figs. 1 and 4, which is detachably secured to the inner wall of the head D, as by some of the screws e', which secure the brush-holders to the ring e''.

F represents a dust cover or ring which encircles the annular portion of the head D, having the inspection-openings e. The dust-ring fits snugly at its inner and outer edges on the annular wall of the head to prevent the entrance of dust, dirt, water, &c., into the machine and is detachably secured in place in some manner, permitting its ready removal to expose the inspection-openings. In the construction illustrated the dust-ring is provided at its inner end with three hooks, Figs. 1 and 3, which engage under the heads of two of the securing-bolts d for the hollow head. When the bolts are tightened up, the dust-ring is securely held; but it can be readily detached by loosening the bolts d and

turning the dust-ring enough to disengage the hooks. The main dynamo is completely inclosed and protected from the weather and from the dust and dirt; but the removable 5 dust-ring affords easy access to the brushes.

The armature and commutator of the main dynamo are removably secured on the armature-shaft, preferably as follows: The armature-shaft is enlarged in diameter between its 10 ends and at one end of the enlarged central portion is provided with a shoulder or flange g . The armature and commutator are carried by a sleeve G , which is keyed or splined on the large central portion of the shaft, with 15 one end against one side of the shoulder g . Surrounding the shaft on the opposite side of the shoulder g is a clamping-sleeve g' , Figs. 1 and 5, having perforated lugs through which pass screws into threaded holes in the armature-sleeve. By tightening the screws the 20 two sleeves are drawn up tightly against opposite sides of the shoulder and firmly secured. This manner of securing the armature-sleeve is much superior to the usual 25 method of fastening the armature on the shaft by a nut or nuts screwed on a threaded part of the shaft, as in such case special threads must be cut on the shaft and nut, and it is a matter of considerable difficulty to attach and detach the parts, usually necessitating special tools. Then, too, the armature 30 is liable to work loose when it is driven in opposite directions, as it is when the apparatus is used in car-lighting. By the construction described the armature can be 35 quickly and easily attached and detached with an ordinary wrench and cannot work loose by reason of the rotation of the armature in opposite directions.

40 H represents the field-magnet frame, and H' the armature of the auxiliary dynamo. This auxiliary field-magnet frame, like that of the main dynamo, preferably consists of an open-ended shell or ring and is detachably 45 secured at its inner end to the outer end of the head D of the main frame, as by screws h . To the outer end of the auxiliary field-frame H is detachably secured, by screws h' , a ring I , which supports the brushes i of the auxiliary 50 dynamo. The open outer end of this brush-supporting ring is closed by a cap or cover K , which is removably secured in place by some suitable means, preferably by bayonet-joints formed by screws k , which project 55 from the sides of the brush-supporting ring I and engage in angular slots k' in the rim of the cap. When the screws are tightened, the cap is securely held in place, and by loosening the screws the cap can be detached in a 60 well-known manner. The auxiliary dynamo is thus also completely inclosed and protected against the entrance of water, dust, &c.; but its brushes can be easily seen and reached for any purpose by removing the cap K . If it is necessary for any reason to

remove the brushes and their holders, this can be done with little trouble by detaching the brush-supporting ring I .

One end of the armature-shaft C projects out through the head D of the main dynamo-frame and has secured thereon the armature H' and commutator l of the auxiliary dynamo. These are preferably carried by a sleeve l' , which surrounds the reduced projecting end of the shaft against a shoulder thereon and is detachably secured in place by a removable pin or key l^2 . 75

The opposite end of the shaft projects from the other head D' of the main dynamo-frame, and on this end of the shaft is detachably secured a chain-wheel M or other wheel for driving the armature-shaft. The end of the shaft is preferably reduced and the wheel splined thereon and secured by a nut m , screwed on the threaded end of the shaft and 85 held from turning by a set-screw m' .

By the described construction the parts of both machines are completely housed or inclosed and protected, and yet access can be easily had to the brushes of the main machine by removing the dust-ring F or to those of the auxiliary machine by removing the cap K . The field-magnet frame and brush-holders of the auxiliary machine can be quickly detached from the main machine by 90 removing the screws h , connecting the field-magnet frame with the head of the main frame, and the armature and commutator can then be slipped off of the armature-shaft when necessary by first removing the securing pin or key l^2 for the armature-sleeve. The armature and commutator of the main machine can also be then removed, together with the armature-shaft by detaching the right-hand head D' of the main machine and 95 drawing the parts out of the right-hand end of the field-frame of the main machine. The armature and commutator of the main machine can also be removed without first dismantling the auxiliary machine, by detaching 100 the drive-wheel M and then detaching the left-hand head D of the main machine-frame and removing the same, together with the armature-shaft and parts secured thereto. The left-hand head D of the main machine, 105 together with the brushes secured thereto and the auxiliary machine, with all of the parts intact, can also be removed to get at the main-machine brushes without disturbing the armature of the main machine by first removing the securing-pin l^2 for the armature-sleeve of the auxiliary machine and slipping the parts off of the armature-shaft. 110

To prevent the lubricating-oil for the bearings from working onto the armature and commutator of the main machine, the inner walls of the hollow heads D D' are provided around the bearing-openings for the armature-shaft with annular catch-pockets N N' for the oil, formed by circular flanges with 115

inturned inner edges. Each catch-pocket (see Figs. 6 and 7) has a drain-hole *n* leading from its bottom into the adjacent lubricating-chamber. The outer end of the commutator-ring *O* of the main machine extends into the catch-pocket *N*, while the outer end of the clamping-sleeve *g'* projects into the other catch-pocket *N'*, and these parts are grooved circumferentially, as shown at *p p'*, respectively. As the commutator-ring and clamping-sleeve rotate with the armature-shaft, any oil which works onto them will be thrown off of their grooved ends by centrifugal force into the catch-pockets to be returned to the lubricating-chambers through the drain-holes *n* and will thus be prevented from reaching the armature and commutator.

The armature of the auxiliary dynamo is also kept free from oil by a similar catch-pocket *Q*, formed in the outer wall of the hollow head *D* and into which the grooved end of the armature-sleeve of the auxiliary dynamo projects.

The bearings and lubricators for the armature-shaft can by the described construction be located at opposite ends of the main dynamo-armature and one between the two machines without danger of the oil getting over the armatures and commutators of the machines.

The main and auxiliary machines are herein described as dynamos; but the construction described would be equally applicable to a dynamo-motor.

We claim as our invention—

1. The combination of a main field-magnet frame, heads closing the ends of said main frame and provided with armature-shaft bearings, an armature-shaft journaled in said bearings and projecting out through one of said heads, a main armature on said shaft and inclosed by said main frame and heads, an auxiliary armature secured to the projecting end of said shaft, an auxiliary field-magnet frame surrounding said auxiliary armature and secured to the adjacent head of said main frame, and a cover closing the outer end of said auxiliary frame, substantially as set forth.

2. The combination of a main field-magnet frame, removable heads closing the ends of said main frame and provided with armature-shaft bearings, an armature-shaft journaled in said bearings and projecting out through one of said heads, a main armature on said shaft and inclosed by said main frame and heads, an auxiliary armature removably secured to the projecting end of said shaft, an auxiliary field-magnet frame surrounding said auxiliary armature and removably secured to the adjacent head of said main frame, and a removable cover or head closing the outer end of said auxiliary frame, substantially as set forth.

3. The combination of main and auxiliary dynamo-electric machines arranged in axial alinement and having an armature-shaft in common, a hollow head located between and detachably connecting the field-magnet frames of the two machines, brushes for the main machines carried by said head, said head together with said brushes and the auxiliary field-frame and armature being removable as a unit from the field-magnet frame of said main machine and said armature-shaft, and said auxiliary field-magnet frame and armature being also detachable from said head and armature-shaft, substantially as set forth.

4. The combination of main and auxiliary dynamo-electric machines arranged in axial alinement, a head located between the field-magnet frames of said main and auxiliary machines and closing one end of each field-magnet frame, said head having openings, and a cover-ring which surrounds said head and is movable to expose said openings, substantially as set forth.

5. The combination of main and auxiliary dynamo-electric machines arranged in axial alinement, a head located between the field-magnet frames of said main and auxiliary machines and closing one end of each field-magnet frame, said head having an annular wall which is of larger diameter than said auxiliary field-magnet frame and is provided with openings, and a detachable cover-ring which surrounds said annular wall and is removable over said auxiliary field-magnet frame, substantially as set forth.

6. The combination of main and auxiliary dynamo-electric machines arranged in axial alinement, a head located between the field-magnet frames of said main and auxiliary machines and closing one end of each field-magnet frame, a brush-supporting ring detachably secured to the outer end of the auxiliary field-magnet frame, and a removable cover closing the outer end of the brush-supporting frame, substantially as set forth.

7. The combination of main and auxiliary dynamo-electric machines arranged in axial alinement, a head located between the field-magnet frames of said main and auxiliary machines and closing one end of each field-magnet frame, brushes for said main machine carried by said head and removable therewith from the main field-magnet frame, a brush-supporting ring detachably secured to the outer end of the auxiliary field-magnet frame, and a removable cover closing the outer end of the brush-supporting frame, substantially as set forth.

8. The combination of main and auxiliary dynamo-electric machines arranged in axial alinement, a hollow head which is located between and connects the field-magnet frames of said main and auxiliary machines and incloses the commutator and brushes for the main machines, said head having a lubricat-

ing-chamber, a shaft for the armatures of said main and auxiliary machines journaled in said hollow head, and oil-guards at opposite ends of the lubricating-chamber of said hollow head to prevent oil from working onto the armatures of the main and auxiliary machines, substantially as set forth.

Witness our hands this 8th day of August, 1905.
